DOOR CHECK

Joseph M. Marin, Beverly Hills, Calif.

Application February 16, 1940, Serial No. 319,283

4 Claims. (Cl. 16—86)

This invention relates to a door check adapted both to silence the closing of a door and to cushion the shock occasioned by quickly closing the door.

5 By this invention a means is provided to utilize both the elastic properties of rubber, or other like materials; and the pneumatic resistance or cushioning effect resulting from the presence of one or more air pockets formed by or in the 10 article.

The invention further relates to a new article of manufacture whereby a door check of the above stated character is provided for attachment to a great variety of door constructions 15 now in use, without making any alterations in structures.

Low cost of manufacture and extreme simplicity of construction are among the objects of the invention.

20 Other objects, advantages and features of invention may hereinafter appear.

Referring to the accompanying drawing, which illustrates what is at present deemed to be a preferred embodiment of the invention,

25 Fig. 1 is a transverse section through a door and its frame, showing the device in its operative position.

Fig. 2 is a front view of the device in its operative position.

30 Fig. 3 is a section of the device on line 3—3 of Fig. 2.

Fig. 4 is a sectional view on line 4—4 of Fig. 2.

In Figs. 2, 3 and 4 the device is shown on a larger scale than in Fig. 1, and a fragment of 35 the door frame is included in each of the former three views.

Referring in detail to the drawing, the article is shown as comprising a flat basal rubber strip 10 having a plurality (two in the illustrated embodiment) of hollow, dome shaped projections 11 upstanding from one of its faces in a longitudinally spaced relation to each other. The space between said projections is occupied by an out-pressed hollow bead 12, and when the article 45 is in its attached position upon the door frame 13 said bead constitutes a projection which affords an air passage way 14 which connects the air chambers 15 of the hollow projections 11.

Attaching means 17 are shown to secure the 50 end portions of the strip 10 to the door frame, the intermediate portion of the strip being left in an unattached relation to the door frame in order that air may enter to refill the chambers 15 and passage 14 when the elasticity of the article 55 causes it to resume normal position after the projections 11 have been more or less flattened by reason of the impact upon them of the edge portion of the hinged door 19.

Owing to the fact that a plurality of small, 60 hollow, air containing, elastic projections are pro-

vided, which extend in a row along the mid-width of the elongated basal strip, an advantage is obtained over the result that would be secured if only a single, though much larger projection, were to be provided; for the small projections provided have ample room, individually, to spread out laterally when the impact of the door against them compresses the air which they contain, whereas a single hollow projection, if made large enough to possess the desired amount of shock-resistance, would require a wider space than that afforded by the door engaging strip which supports it.

Owing to the fact that the bumper, including its impact receiving wall portions, is made of a soft, spongy rubber, when an impact is received the small air spaces in the cells of its walls co-operate with the large air spaces 15 to secure a better cushioning effect.

20 A layer of adhesive or cement 20 is shown underlying each end portion of the strip to serve as an attaching means instead of tacks or screws, if desired. Whichever kind of attaching means is used the intermediate portion of the strip should be left in an unattached or loosely overlying relation to the door frame.

I claim:

1. An elastic door bumper comprising a flat basal part securable to a door frame and a plurality of pneumatic hollow projections extending in a row from the same face of said basal part, there being spaces between adjacent projections to allow them to expand when subjected to an impact.

2. The subject matter of claim 1 and, there being a passage which connects the interiors of said projections with each other when the device is in its attached position.

3. An elastic door bumper comprising a flat, elongated, basal strip of rubber attachable to a door frame and furnished with two hollow projections upstanding from one of its faces in a longitudinally spaced relation to each other, said strip having an up-pressed bead occupying the space between said hollow projections and affording an air passage between them.

4. As an article of manufacture, an elongated flat strip having a pneumatic, chambered shock absorbing projection located at each side of its mid-length and in a spaced relation to an end thereof, there being a bead in said strip which affords air communication between said projections, the chambers of said bead and projections all opening out through the basal face of the strip, and attaching means for said strip confined to its end portions thereby providing for leaving the side portions of the mounted strip opposite to its chambers and passage in an unattached relation to the door frame.
